UNITED STATES PATENT OFFICE.

WILLIAM J. LAWRENCE, OF TOLEDO, OHIO.

FURNACE.

Application filed February 19, 1920. Serial No. 360,008.

To all whom it may concern:

Be it known that I, WILLIAM J. LAWRENCE, a citizen of the United States, residing at Toledo, in the county of Lucas and State of Ohio, have invented new and useful Improvements in Furnaces, of which the following is a specification.

My invention relates to furnaces and particularly to automatic means for regulating the supply of air to the burning fuel in boiler furnaces and the like which are given fresh charges of coal at frequent intervals. When a fresh charge of bituminous coal is spread over an incandescent fuel bed, the coal is heated rapidly and 20% to 40% of the combustible matter is distilled off in the form of gases and tar vapors. This process is usually nearly completed in two to five minutes after firing. The distilled combustible matter requires for its combustion a large amount of additional air. To burn the volatile combustible material, about fifteen times its weight of air must be supplied thereto, so that immediately after firing, a large quantity of air should be admitted over the fire and this quantity should be gradually reduced as the distillation of the volatile combustible nears completion. After distillation is completed only a comparatively small quantity of air need be admitted over the fuel bed.

The primary object of my invention is to provide automatic means for supplying the air in the required amount immediately after each fresh charge of fuel has been introduced to the furnace and to gradually reduce this amount so that the proper supply of air is furnished at all times. This results in complete combustion, high efficiency and economy of fuel, and elimination of smoke.

In carrying out my invention I provide suitable means operated by the feed door of the furnace to control the supply of air. The arrangement is such that the closing of the feed door after each fresh charge of coal is introduced, automatically opens the dampers which regulate the supply of air to the furnace, so that air is admitted in sufficient volume to effect complete combustion. The dampers are then automatically gradually moved toward a closed position to effect a corresponding reduction of the air supply, the movement being controlled by

a dash pot or other retarding element, so that after the volatile combustibles have been burned the supply of air is restricted to the comparatively small amount then needed. Loss of heat due to an excess of air is thus prevented.

Other features of the invention will appear hereinafter.

In the accompanying drawings:

Figure 1 is a sectional elevation of a furnace constructed in accordance with my invention, portions of the furnace being omitted.

Figure 2 is a sectional plan of that portion of the furnace on one side of the longitudinal center line.

Figures 3 and 4 are sectional elevations at the plane of the line A—B, showing respectively the draft dampers in closed and open positions.

Figures 5, 6 and 7 are front elevation views of the furnace, showing the damper controlling devices in different positions. Figure 5 shows the feed door closed and the dampers down in their normal or draft-checking position. Figure 6 shows the furnace door open for introducing a fresh charge, the dampers still being down while the feed door remains open. Figure 7 shows the position of parts immediately after the furnace door has closed, the dampers being now open.

Figure 8 is a detail view on a larger scale of the damper controlling mechanism.

Figure 9 is a fragmentary view of such mechanism looking in a direction at right angles to that of Figure 8.

The furnace comprises a combustion chamber 10 in the front wall of which is an opening 11 for the introduction of fuel, said opening being normally closed by the feed door 12. The air for combustion enters ports 13 beneath the grate bars 14 and passes upward through passageways 15 in the side walls of the furnace, being thereby pre-heated, and enters the combustion chamber through the ports 16 above the grate. The gases of combustion are conveyed rearwardly in the general path indicated by the arrows, passing beneath a baffle wall 17 and thence rearwardly beneath the boiler 18.

The baffle wall 17 serves to secure an even distribution of the air over the fire bed by preventing the air from forming currents

or flowing in restricted paths or channels over the fire bed. By admitting the air through the ash pit or below the grate and passing it upward through the side walls of the furnace, it is heated to a high temperature before entering the combustion chamber, thus increasing the efficiency.

The amount of air admitted to the combustion chamber is controlled by dampers

- 10 20 and 21 arranged over the openings 13 and which normally restrict the amount of air admitted to said openings. These dampers are automatically swung upward to a wide open position by the closing of the feed door
- 15 11 after a fresh charge of fuel has been introduced. The dampers are then permitted to gradually swing down, for the purpose already pointed out. The mechanism for operating and controlling the dampers will
- 20 now be described.

A link 22 is pivotally connected at one end to the feed door 12 and at its opposite end is connected by a pivot 23 to a bar 24 slidable lengthwise in guide brackets 25 and 26.

- 25 Above the slide bar 24 is a rock shaft 27 to which is fixed a lever 28. One end of said lever is connected through a vertical link 29 to an arm 30 connected to the damper 20. The rod 29 may also be connected
- 30 through a link 31 with an arm on the damper 21. The other end of the lever 28 is connected through a link 32 and piston rod 33 to the piston 34 of a dash pot 35. Said piston may be provided with a valve
- 35 36 opening upward to permit the piston to move downward freely, a restricted opening 37 being provided to allow a slow upward movement of the piston, which may work in oil. A crank arm 40 is adjustably
- 40 secured to the shaft 27 by a set screw 41 (Fig. 9). Pivoted to said crank arm is a dog 42. The downward movement of the dog about its pivot is limited by a shoulder
- 45 43 which engages with the arm 40. An adjustable lug 44 is mounted on the slide bar 24 in position to engage in front of the dog 42 when the feed door is opened.

- 50 Normally the parts are in the position shown in Figure 5. When the attendant opens the feed door to introduce a fresh supply of fuel, the slide bar 24 is moved to the left to the position indicated in Figures 6 and 8, permitting the dog 42 to drop behind the lug 44. When the attendant closes
- 55 the feed door, the bar 24 is thereby pulled to the right and through the dog 42 and arm 40, rocks the shaft 27 in a counter clockwise direction, thereby rocking the lever 28 to the Figure 7 position. This moves the
- 60 piston downward in the dash pot and at the same time through the connections 29, 30 and 31 swings the dampers 20 and 21 upward to the wide open position. As the feed door is being closed, the dog 42 is carried
- 65 upward by the upward movement of the arm

40 sufficiently to disengage the lug 44 and permit it to move to the right of the dog, so that the latter is free to swing from the Figure 7 position back to the Figure 5 position independently of said slide bar, the feed door remaining closed.

After the feed door is closed the weight of the dampers and connected parts slowly returns the mechanism to the Figure 5 position. It will thus be seen that while the feed door is open the dampers remain down, but they are automatically opened wide by the closure of the feed door, permitting a large volume of air for the combustion chamber, which is required to produce complete combustion of the volatile elements which are rapidly given off from the fresh fuel. This supply of air is then gradually reduced at a rate corresponding to the reduction of the volatile elements, so that when the latter are burned out, the supply of air is limited to the comparatively small amount needed to sustain the continued combustion.

Although the dampers on both sides of the furnace are shown as operated from a single door, it will be understood that when double doors are used the dampers on opposite sides may be conveniently operated separately by the two doors. The dash pot 35 is shown merely as an example of a retarding device, as various other standard or approved retarding devices might serve the same purpose. It will also be understood that various modifications of the damper controlling mechanism might be employed and that these and other changes or modifications may be resorted to within the spirit and scope of my invention.

What I claim is:

1. In a furnace, the combination of a combustion chamber, a grate therefor, the side walls of said chamber being formed with air passages extending from beneath the grate and opening into the combustion chamber above the grate, dampers controlling said passages, a fuel door, means operated by the closing of said door to open said dampers, and automatic means to effect a gradual movement of the dampers toward closed position.

2. In a furnace, the combination of a combustion chamber, a grate therefor, the side walls of said chamber being formed with air passages extending from beneath the grate and opening into the combustion chamber above the grate, dampers controlling said passage, mechanical connections between the dampers and the feed door of the furnace for opening the dampers by the closing of the door, and automatic means to then cause a slow movement of the dampers toward closed position.

3. A furnace comprising in combination a combustion chamber, a grate, the side walls

of the furnace being provided with air channels leading from the ash pit beneath the grate upward through the furnace walls and opening into the combustion chamber above the grate, dampers beneath the grate controlling said channels, means operated by the closing of the feed door to open

said dampers, and automatic means to cause a slow closing of said dampers after the feed door is closed.

10

Signed at Toledo, in the county of Lucas and State of Ohio, this 12th day of February, 1920.

WILLIAM J. LAWRENCE.
